C. M. Lufkin,
Harvester Cutter

No. 14874

Patented. May 13, 1856.

UNITED STATES PATENT OFFICE.

C. M. LUFKIN, OF ACKWORTH, NEW HAMPSHIRE.

IMPROVEMENT IN MOWING-MACHINES.

Specification forming part of Letters Patent No. 14,874, dated May 13, 1856.

To all whom it may concern:

Be it known that I, C. M. LUFKIN, of Ackworth, in the county of Sullivan and State of New Hampshire, have invented a new and Improved Mowing-Machine; and I do hereby declare that the following is a full, clear, and exact description of the same, reference being had to the annexed drawings, making a part of this specification, in which—

Figure 1 is a transverse vertical section of my improvement, *xx*, Fig. 2, showing the plane of section. Fig. 2 is a plan or top view of the same.

Similar letters of reference indicate corresponding parts in the two figures.

To enable those skilled in the art to fully understand and construct my invention, I will proceed to describe it.

A represents the main frame of a mowing-machine, and B is the driving-wheel fitted therein.

To the lower end of the frame A, and at one side, there are attached two bars, having each circular projections or plates C formed on them. The bars and plates are placed one above the other, a space being allowed between them.

Between the plates C of each bar there are placed two circular toothed cutters, D D'. The upper cutters D' have beveled wheels a attached to their centers—one to each—and the upper plates C have circular holes cut through their centers, said holes being slightly larger and concentric with the bevel-wheels a, or nearly so.

To each of the upper plates C there is attached an arm, E. These arms project over the centers of the bevel-wheels a and form upper bearings for small vertical shafts b, the lower ends of the shafts b being stepped at the centers of the lower plates C and passing loosely through the centers of the wheels a. The upper ends of the shafts b have bevel-wheels c attached to them.

F is a shaft, which is placed over the upper plates C and longitudinally with the bar of said plates. This shaft passes through the arms E, which form bearings for said shaft. One end of the shaft has a pinion, G, upon it, and this pinion gears into a toothed wheel, H, attached

to the spokes of the driving-wheel B. The shaft F has bevel-wheels d upon it, which gear in the bevel-wheels a on the lower circular cutters, D, and also has bevel-wheels e upon it, which gear into the bevel-wheels c on the shafts b. The lower cutters D are attached to the shafts b.

I is a shaft, placed parallel with the shaft F, and having its bearings on the arms E. This shaft has rollers f upon it, around which endless aprons J pass, said aprons also passing around rollers g, which have their bearings in uprights h, attached to the front parts of the upper plates C. The endless aprons are placed between the gearing of the several cutters, the gearing of each pair of cutters being covered by a cap, K, and the aprons have slats or ledges a secured transversely on them. The shaft I is driven by gearing i from the shaft F.

To the front parts of the lower plates C there are attached fingers or guards, L, the outer ends of which are hooked or bent upward, as shown clearly in Fig. 1.

The cutters D D' are formed of circular steel plates, which are placed in pairs, one over the other, and provided with teeth on their peripheries, one side of which is beveled to a cutting-edge, the cutting-edges of the teeth of one plate being on sides opposite to those of the other.

The operation is as follows: As the machine is drawn along the toothed wheel H on the driving-wheel B will rotate the shaft F, and the bevel-wheels d on said shaft will rotate the upper cutters D in one direction, while the bevel-wheels e on the shaft will rotate the wheels c and lower cutters D', which are attached to the shafts b, in an opposite direction. The grass passes between the fingers or guards L and is cut by the cutters, the teeth operating like shears, and the cut grass is carried over the cutting device by the endless aprons J and falls upon the ground back of the cutters. The hooked or bent fingers or guards prevent stones from coming in contact with the cutters. By having their ends bent upward they offer a complete barrier to stones.

The above-cutting device will cut grass effectually even if "lodged" or bent toward the ground. The cutters are not liable to become

clogged, nor are any parts liable to get out of repair. | D', arranged as shown, for the purpose specified.

Having thus described my invention, what I claim as new, and desire to secure by Letters Patent, is—

The employment or use of the endless aprons J in connection with the rotating cutters D

C. M. LUFKIN.
